UNITED STATES PATENT OFFICE

98,665

DESIGN FOR A PLANT CONTAINER

Leon H. Elmer, San Jose, Calif.

Application December 16, 1935, Serial No. 60,098

Term of patent 7 years

To all whom it may concern:

Be it known that I, Leon H. Elmer, a citizen of the United States, residing at San Jose, county of Santa Clara, and State of California, have invented a new, original and ornamental Design for a Plant Container, of which the following is a specification, reference being had to the accompanying drawing, forming a part thereof.

The figure is a perspective view of a plant container showing my new design. The sides not shown are substantially identical in appearance with the side shown in the drawing at the left of the side having the elongated opening thereon.

I claim:

The ornamental design for a plant container, substantially as shown and described.

LEON H. ELMER.
